UNITED STATES PATENT OFFICE

2,373,423

BOX

Frank C. Shina, Urbana, Ohio, assignor to United
Paperboard Company, New York, N. Y., a cor-
poration of New Jersey

Application November 27, 1942, Serial No. 467,138

2 Claims. (Cl. 229—39)

The present invention relates to a novel box. More particularly the present invention relates to a novel box of the snap-lock type.

Although boxes of this type are known in the art, in general they included relatively complex structures having a plurality of projecting tabs or the like which made them difficult to manufacture. The use of small projecting tabs also rendered the box more fragile, i. e., the small tabs were easily torn from the blank and thereafter the box was unusable.

In my U. S. Patent No. 2,339,656, there is disclosed a box which did not include any projecting tabs or the like and was relatively simple and easy to manufacture. This type of box, however, while in the main satisfactory, was not entirely suitable for the larger sizes of boxes.

It is one of the objects of the present invention, therefore, to provide a box construction of the snap-lock type which is suitable for almost any size construction.

A further object of the present invention is to provide a box of the snap-lock type wherein a simple manual pressure will simultaneously interlock the flaps thereof in such position as to resist opening movement by relatively heavy loads.

A third object of the present invention is to provide a box easily locked by simple manual pressure including a pair of bottom flaps and top flap cooperating with both of said bottom flaps and with an intermediate flap to retain said intermediate flap in position.

A fourth object of the present invention is to provide in a box of the character described a simple interlocking box construction wherein a plurality of end flaps are each interlocked with a single end flap having marginal edges extending along fold lines of adjacent flaps to aid in preserving the shape of the box.

A fifth object of the present invention is to provide a box construction wherein a simple upper flap cooperates with a plurality of underlying flaps to form a secure snap-locking closure for a box end.

A sixth object of the present invention is to provide a box construction wherein an upper flap member may be easily interlocked with a pair of opposed bottom flap members and including an intermediate flap member retained in position by said upper flap and cut away to permit interlocking of said upper flap and bottom flaps.

Other objects and advantages of the present invention will become apparent from the sub-

sequent description and figures of the drawings wherein:

Figure 1 is a blank of a box according to the present invention;

Figure 2 is a perspective view of the box of the present invention with the bottom flaps and intermediate flap in position;

Figure 5 is a perspective view of the box of the present invention with the upper flap being pressed into locking position;

Figure 4 is a perspective view similar to Figures 2 and 3 with the flaps in final interlocked position;

Figure 5 is a section taken on the line 5—5 of Figure 4;

Figure 6 is a section taken on the line 6—6 of Figure 4;

Figure 7 is an enlarged detail section of a portion of Figure 5.

Referring to the drawings, and particularly Figure 1 thereof, a box blank is indicated in general at 10. The blank 10 is provided with a glue flap 11 and side portions 12, 13, 14 and 15 respectively. The glue flap 11 is separated from the side 12 by the vertical fold line 16 and the sides 12, 13, 14 and 15 are separated by the fold lines 17, 18 and 19 respectively.

Projecting from the sides 13 and 15 and separated therefrom by the horizontal fold lines 20 and 21 are conventional side flaps 22 and 23. Similarly, projecting from the side 15 is a conventional outer flap 24 separated from the side 15 by a fold line 25. The flap 24 is also provided with a tuck-in flap 26 separated from the remainder of the flap 24 by a fold line 27. As may be understood, the flaps 22, 23 and 24 form a conventional closure for one end of the box 10. Further, the glue flap 11 may be glued or otherwise fastened to the side 15 to form a box.

The particular closure of the present invention includes the flaps 28, 29, 30 and 31. As shown, the flap 28 extends from the side 12 and is separated therefrom by the fold line 32, while the flaps 29, 30 and 31 extend from the sides 13, 14 and 15 and are each separated from its respective side by the fold lines 33, 34 and 35. The flap 28 is cut away or notched at its end edge, as indicated at 36, and is further cut away or notched at each marginal edge or side edge as indicated at 37 and 38 for a purpose to be hereinafter described. It will be noted in particular that the cutaway portion or notched portion 36 is wider at its outer edge than at its inner edge as the two sides defining the notched portion 36 and indicated at 39 and 40 respectively slant inwardly slightly

from the edge 41 proper of the flap 28. It will also be noted that the edge portions 42 and 43 bounding the notched portions 37 and 38, form an acute angle with the vertical axis of the box.

Each of the flaps 28 and 31 is provided with a slit 44 and a slit 45 respectively, forming an acute angle with the fold lines 34 and 35 and extending therefrom toward the mid portions of the flaps. Short cross slits 46 and 47 extend transversely to form displaceable portions 48 and 49.

The end edge of the flap 30 is notched at 53 and 54 to form a projecting tab 52 of a size and positioned to interlock with the notch 36 of the flap 28.

Referring to Figure 2, the box 18 is shown glued and folded into rectangular shape. The flaps 28 and 30 have been bent at the fold lines 33 and 35 so that they are opposed to one another and at right angles to sides of the box. The flaps 28 and 30 thus constitute bottom flaps and also folded upon these bottom flaps is the intermediate flap 28. It will be noted that in this position the side notches of the flap 28 extend beyond the slits 44 and 45 due to the angle and length of the side edges 42 and 43. It will also be noted that the side edge portions 53 and 54 also bounding the notches are in general parallel to the slits 44 and 45.

In Figure 3 the upper flap 30 has been bent over along the fold line 34 and pressed inwardly so that the marginal edges indicated at 55 and 56 displace downwardly the portions adjacent the slits 44 and 45 to allow the entry of the side marginal edges 53 and 54. At the same time the tab 52 and end edge of the flap 30 is pushed downwardly so that the tab 52 enters the notch 36. When, therefore, the flap 30 is released and returns to the position of Figure 4 the end edges of the flaps 28 and 30 are interlocked with the tab 52 in the notch 36. Due to the slanting edges 39 and 40, the interlock is easily effected. In addition the marginal edges 55 and 56 of the flap 30 are extended through the slits 44 and 45 to lie along the inner surface of the fold lines 33 and 35. This latter arrangement braces the box and preserves its shape. It is evident therefore that the flap 30 is interlocked and retains in position all of the other flaps forming the closure. The close proximity of all of the interlocks strengthens the entire closure and prevents opening thereof under relatively heavy loads.

What is claimed is:

1. In a box construction including four side walls, end flaps projecting from said side walls toward an opposed side wall and connected with each respective side wall by a fold line, one pair of opposed flaps constituting bottom flaps and being each provided with slits extending from the respective fold line of each flap in position to receive respective marginal edges of another flap constituting an upper flap, cross slits in said bottom flaps extending transversely from the first mentioned slits and forming with said first mentioned slits displaceable portions for facilitating the entry of said marginal edges into said first slits, said marginal edges when extended through said first slits lying along the fold lines connecting said lower flaps and their sides so as to aid in maintaining the shape of said box, and a fourth flap having a substantial portion lying intermediate the first pair of flaps and the upper flap so that said upper flap when extended through said first slits will retain said intermediate flap in position, said last flap having cut-away portions adjacent said first slits to permit entry of said marginal edges into said slits.
2. In a box construction including four side walls, end flaps projecting from said side walls toward an opposed side wall and connected with each respective side wall by a fold line, one pair of opposed flaps constituting bottom flaps and being each provided with slits extending from the respective fold line of each flap in position to receive respective marginal edges of another flap constituting an upper flap, cross slits in said bottom flaps extending transversely from the first mentioned slits and forming with said first mentioned slits displaceable portions for facilitating the entry of said marginal edges into said first slits, said marginal edges when extended through said first slits lying along the fold lines connecting said lower flaps and their sides so as to aid in maintaining the shape of said box, a fourth flap lying intermediate the first pair of flaps and the upper flap so that said upper flap when extended through said first slits will retain said intermediate flap in position, said last flap having cut-away portions adjacent said first slits to permit entry of said marginal edges into said slits, and means on the end margin of said fourth flap interengaging with means on the end margin of said upper flap.

FRANK C. SHINA.
